UNITED STATES PATENT OFFICE.

ERVAN L. McDONALD, OF SALT LAKE CITY, UTAH.

METHOD OF AND APPARATUS FOR MAKING ELECTRICAL MEASUREMENTS.

1,286,373.

Specification of Letters Patent.

Patented Dec. 3, 1918.

Application filed May 8, 1914. Serial No. 837,317.

To all whom it may concern:

Be it known that I, ERVAN L. McDONALD, a citizen of the United States, residing at Salt Lake City, in the county of Salt Lake and State of Utah, have invented certain new and useful Improvements in Methods of and Apparatus for Making Electrical Measurements, of which the following is a specification.

10 My invention relates to an improved adjustable inductance coil adapted for use in making electrical measurements, and for various other purposes, in connection with electric circuits connected to alternating or pulsating electromotive forces. For example, the apparatus is of particular advantage in connection with my improved method of measuring or comparing electrical resistances, capacities, inductances, and 20 other characteristics of electrical circuits, as briefly set forth herein, and as more particularly described in my copending application Serial No. 107,706, filed July 5, 1916, which is a division of this application.

25 The principal object of this invention is to provide an apparatus comprising an inductance coil mounted in fixed position, in combination with a movable contact arranged to make contact with any desired 30 turn of said coil throughout its length and throughout the periphery of the coil. A further object is to provide means for making contact with the inductance coil at any desired point between its ends, in combination with means for accurately determining the relative proportions of the coil on each 35 side of the contact point. Still another object is to provide an improved contact for making electrical connection with a turn of the coil throughout the periphery thereof. Other objects relate to various features of construction and arrangement which will appear more fully hereinafter.

40 Other characteristics and advantages of my invention will be set forth and made apparent in the following specification, of which the accompanying drawings form a part.

In the drawings—

45 Figure 1 is a diagrammatic view of the general arrangement and connections of my apparatus, showing the uniform and symmetrical arrangement of the turns of the inductive coils.

50 Fig. 2 is a plan view of my apparatus assembled in permanent form on a base plate,

the connections for actual operation not being shown.

Fig. 3 is a detail plan view of a contact member showing a portion of a coil with 60 which said member makes contact.

Fig. 4 shows a side elevation of the contact member.

Fig. 5 shows an elevation of the inner side of one of the insulating rings of the 65 contact member.

Fig. 6 shows a side elevation of the rotating conducting ring of the contact member.

Fig. 7 shows a sectional view of the insulating rings and the conducting ring in 70 assembled relation.

Fig. 8 is an enlarged sectional view showing the means for making contact with a single turn of the coil; and

Fig. 9 is a partial side elevation of the 75 conducting ring showing the means for making contact with a turn of the coil.

Like numerals refer to like parts and elements in the several figures of the drawings, in which my invention is shown as comprising two electrical conducting coils 10 and 11, which are inductively wound on the same core. Each coil is made up of a plurality of turns which are insulated from each other and from the turns of the other 80 coil, the outer coil 11 being wound concentrically with the coil 10 and in close proximity thereto. The two coils are of equal length, preferably made up in sleeve-like 85 form and mounted upon a base plate 12 of insulating material, as shown in Fig. 2. The terminals 10^a and 10^b of the coil 10 are connected by means of the electrical conductors 13 to binding posts 14, which are permanently fixed on the base plate 12. 90 The terminals 11^a and 11^b of the coil 11 are connected by means of the electrical conductors 15 to the binding posts 16 and 17, which are also permanently secured to the base plate. A portion of the peripheral 95 surface of the coil 11 is uninsulated, so that each of the turns of said coil is exposed on the outer periphery thereof, in order that an electrical contact can be made with said coil at any point between its ends. A guide 100 rod 18, preferably of rectangular cross section, is mounted upon the base plate, parallel to the coils 10 and 11, and has slidably mounted thereon a member 19 which carries the contact member 20 adapted to make an 105 electrical connection with the exposed portions of the turns of the coil 11 at any point

110

2

between the ends of said coil. A graduated scale 21 is secured to the base plate parallel to the guide rod, and a pointer 20^a, carried by the sliding member 19, is adapted to project over the graduations on the scale. An electrical conductor 22 connects the sliding member and contact member with a binding post 23, which is secured to the base plate adjacent the binding posts 16 and 17. 5 Opposite the binding posts 23, 16, and 17 are the respective binding posts 24, 25, and 26, which are also secured to the base plate. A common connecting plate 27, of conducting material, is secured to the base plate 15 adjacent the last-named binding posts, and has fixed thereon the binding posts 37, 28, and 29. By means of the binding posts 14, the inner inductive coil 10 can be connected in circuit with a galvanometer 30, or other 20 detector of feeble currents.

In order to insure greater accuracy in the adjustment of my apparatus I provide a contact member 20 of special form. The outwardly extending portion of the sliding 25 member 19, which carries the contact member 20, is bifurcated, as shown clearly in Fig. 3, to form two forked arms 39, each of which is provided with an arcuate flange 39^a having an inner surface adapted to conform to 30 a portion of the outer contour of an insulating ring 40. Each of these insulating rings is concentric with and has an inner ring 35 diameter slightly greater than the outer diameter of the coil 11, and is secured to its corresponding arcuate flange 39^a by suitable screws, or other means of fastening. The inner plane faces of the rings 40, which are 40 then spaced apart, serve as guides or bearings for a rotatable conducting ring 41, which carries means for making electrical 45 contact with a single turn of the coil 11 at any point around the periphery thereof after the sliding member 19 has been moved to the desired position longitudinally of the 50 coil. The conducting ring 41 has an inner diameter greater than the inner diameter of the rings 40, and is provided on each side with a concentric annular flange 41^a, which is journaled in a corresponding annular 55 groove 40^a in the adjacent insulating ring 40. The ring 41 is thus maintained in proper relation to the coil 11, and is prevented from forming an electrical contact therewith, except as hereinafter described. 60

The ring 41 is provided at some point on the inner side thereof with a notch 42 having an arcuate surface 43, upon which is mounted a spring connector 44, whose head 45 is adapted to make contact with the outer 65 surface of a turn of the coil 11. As shown in Fig. 8, the head has a surface conforming to the contour of the conductor of the coil, so that said head will—under the influence of its spring—maintain contact with 85 a single turn of said coil upon rotation of

the ring 41. The head 45 is also beveled at each side of its contacting surface so that it will readily slide over successive turns of the coil, as the entire contact member 20 is moved longitudinally of the coil on the 70 guide rod 18. Radially outward of the head 45 the ring 41 carries a fixed pointer 46, whose diametrically opposite points 46^a project over graduations 40^b on the insulating rings 40, as shown in Fig. 3. 75

The sliding member 19 carries a binding post 47, to which the conductor 22 leading from the binding post 23 is fastened. The binding post 47 is preferably insulated from the member 19, and is provided with an insulated conductor 48, by means of which an electrical connection is made between the conductor 22 and a spring contact 49, which is secured to, but preferably insulated from, an arm 39 of the member 19 and adapted to 80 project into a slot in one of the rings 40 to make electrical contact with the ring 41, as shown at 59. Since the operator of the apparatus moves the contact member longitudinally of the coil 11 by means of the sliding member 19, the binding post 47 and associated parts are preferably insulated therefrom, as stated, in order that said member will form no part of the electrical circuit. The member 19 is threadedly engaged 85 by a stud 19^a, which may be operated by means of a knurled head 19^b to engage the guide rod 18, and thereby secure the contact member 20 in any desired position longitudinally of the coil 11. 90

It will be apparent that by means of a contact member 20, of the form just described, an electrical connection is made between the conductor 22 and a single turn of the coil 11 at any point around the periphery thereof. A ring 40 being properly graduated to indicate the decimal parts of a turn of the coil 11, the operator may from the positions of the pointers 20^a and 46 determine the number of turns and fractional 105 parts thereof which are included in each portion of the coil 11 at each side of the point where an electrical contact is made therewith by the contact member 20. The rings 40 may be graduated to read in opposite directions, and two points 46^a provided on the fixed pointer 46 so that the fractional part of a turn included in each portion of the coil 11 at corresponding sides of the contact member 20 may be read directly or the 110 graduations may be placed on the ring 41 and the indicators attached to the rings 40. In order to facilitate the reading of the position of the pointer 46 when it is on the under side of the coil 11, a mirror or other 115 suitable means may be adopted to indicate the reading to the operator in his position above the coil. 120

I have above described the parts of my apparatus which I prefer to assemble in 130

permanent form on the base plate or standard, so that the apparatus may be conveniently moved from one position to another to be at all times in readiness for operation. Referring to Fig. 1, I have shown diagrammatically the connections of my apparatus which are used for measuring or comparing the resistance of electrical conductors. The two resistances 31 and 32, which are to be compared, are connected between the respective pairs of binding posts 25 and 16 and 26 and 17, the binding posts 25 and 26 being electrically connected to the common connecting plate 27, or to the ground, as preferred. The electrical conductors 33, leading from a source of alternating current E. M. F. or other suitable supply are connected to the binding posts 23 and 24. Thus it will be seen that one terminal of the source of electric pressure is connected to the sliding contact member 20. The other terminal of this source of pressure is connected to the common connecting plate 27, or to the ground, in case the binding posts 25 and 26 have been connected to the ground. Referring to Figs. 1 and 2 it will be apparent that two parallel electric circuits are formed between the contact member 20 and the common connecting plate 27 as follows: the circuit 20, 11^a, 16, 31, 25, and 27, and the circuit 20, 11^b, 17, 32, 26 and 27.

It is therefore apparent that the current entering the coil 11 from the contact member 20 will at any given instant be flowing in opposite directions from the contact member in the two portions of the coil at each side thereof. The inductive action of one portion of the coil will therefore be opposed to that of the other portion, so that when these two actions are unequal a current will flow in the coil 10, in response to the voltage induced therein, and cause a deflection or indication of the galvanometer or other detector 30. When the inductive action of the two portions of the coil 11 on corresponding portions of the coil 10 just neutralize each other there will be no flow of current in the circuit of the coil 10 and no deflection or indication of the galvanometer or other detector.

Having connected my apparatus as above described, the sliding member 19 is adjusted longitudinally of the coil 11 and the contact member 20 manipulated until the inductive effect of one of the above named branch circuits just balances that of the other branch circuit. In making this adjustment the contact member 20 is moved longitudinally of the coil until a point is reached where the detector 30 indicates an approximate balance. The ring 41 is then adjusted within the insulating rings 40 until an exact balance is found. When this point of balance is reached the current induced in the coil 10 will be zero, owing to the fact that the inductive effect of the two portions of the coil

11 on each side of the contact member will just neutralize each other, with the result that the voltages induced in the corresponding proportional parts of coil 10 will neutralize each other. Thus, the point of balance will be indicated by the galvanometer or detector 30, which will fail to register when this point in the adjustment has been reached. The scale 21 being graduated according to the number of turns in the coil 11, the relative number of turns and fractional parts thereof in the two portions of said coil at each side of the contact made by the contact member 20 can readily be determined by reading the indications made by the pointers 20^a and 46 on their corresponding scales. The values of the resistances 31 and 32 will then be directly proportional to the number of turns in the two portions of the coil 11 at each side of the contact member, and if one of the resistances 31 or 32 be a known or standard resistance, the value of the other may readily be calculated from the proportion which the number of turns in the two portions of the coil 11 bear to each other, all of which will be readily understood by anyone skilled in the art to which this invention appertains.

I preferably wind the coils 10 and 11 upon a core of non-magnetic material, since I have found that the results following the use of my apparatus are more accurate when an air core is used than when a core of magnetic material is employed. The accuracy of the results is also increased by constructing the coils of my apparatus with a relatively low resistance. The speed with which the apparatus may be used may be augmented by graduating the scale 21 to read in both directions, and this also provides a quick and convenient means for checking results by reversing the position of the two elements under test.

It will be understood that my apparatus is capable of other uses than herein described for purposes of illustration, and for further description of the use of the invention herein described reference is made to my copending application above referred to, in which the method of and apparatus for making electrical measurements are described and claimed.

I have explained my invention in connection with one particular form and arrangement of apparatus, but it will be obvious that it may be embodied in other forms of apparatus which may be operated upon the principles which have been set forth herein in connection with the particular form of apparatus described, and I do not therefore wish to be limited to the particular form and arrangement of apparatus herein described. It will be understood that I contemplate changes in form and arrangement and the substitution of equivalents without depart-

ing from the spirit of the invention as defined in the appended claims.

I claim:—

1. In apparatus of the class described, an electrical coil wound in sleeve form, a guide extending around the periphery of said coil, and a movable contact element slidably mounted on said guide to contact with said coil at any point around the periphery thereof.
2. In apparatus of the class described, an electrical coil wound in sleeve form, a guide extending around the periphery of said coil, a movable contact element slidably mounted on said guide to contact with said coil at any point around the periphery thereof, and supporting means for said guide adapted to permit movement thereof longitudinally of said coil.
3. In apparatus of the class described, a coil, a contact member movable longitudinally of said coil and arranged to contact with any desired turn thereof at any point around the periphery thereof, said contact member comprising relatively movable members, one of said members having graduations thereon, and a pointer carried by the other member.
4. In apparatus of the class described, an electrical coil wound in sleeve form with the turns thereof insulated from each other, and a contact member slidably mounted to move longitudinally of said coil, said contact member comprising a movable part adapted to extend around said coil and to contact with any desired turn thereof at any point around the periphery of the coil.
5. In apparatus of the class described, a coil wound in sleeve form and mounted in fixed position, the turns of said coil being insulated from each other but having their outer surfaces uninsulated, a contact member movable longitudinally of said coil, and a guide for said contact member mounted alongside said coil, said contact member comprising a part movable throughout the circumference of said coil to contact with any desired turn of said coil at any point throughout the periphery thereof.
6. In apparatus of the class described, an electrical conductor wound in sleeve form to form a coil, an annular guide member extending around said coil, a contact member slidably mounted on said guide member and having a part adapted to engage any desired turn of said coil, a supporting

bracket for said guide member, and a member upon which said guide member is slidably mounted to move longitudinally of said coil.

7. In apparatus of the class described, an electrical conductor wound in sleeve form to form a coil, a pair of annular insulating members extending around said coil, a conducting member rotatably mounted between said insulating members, a contact element mounted on said conducting member to engage a turn of said coil, means to indicate the relative position of said contacting member with respect to said insulating members, and means to permit bodily movement of said insulating members and said conducting member longitudinally of said coil.

8. In apparatus of the class described, an electrical conductor wound in sleeve form to form a coil, a guide member mounted parallel to said coil, supporting means slidably mounted on said guide member, a pair of annular insulating members carried by said supporting means and extending around said coil, an annular conducting member having lateral flanges, said insulating members having annular grooves to be slidably engaged by said flanges, and a contact element resiliently mounted on said conducting member and adapted to engage a turn of said coil.

9. In apparatus of the class described, an electrical conductor wound in sleeve form to form a coil, a guide member mounted parallel to said coil, supporting means slidably mounted on said guide member, a pair of annular insulating members carried by said supporting means and extending around said coil, an annular conducting member having lateral flanges, said insulating members having annular grooves to be slidably engaged by said flanges, a contact element resiliently mounted on said conducting member and adapted to engage a turn of said coil, means to indicate the position of said supporting means longitudinally of said coil, and means to indicate the relative position of said contact element around the periphery of the turn of said coil engaged thereby.

In testimony whereof, I have subscribed my name.

ERVAN L. McDONALD.
